CLAIM

The ornamental design for an orthopedic back support pillow, as shown.

DESCRIPTION

FIG. 1 is a top front, and left side perspective view of the orthopedic back support pillow showing my new design;

FIG. 2 is a top, rear and right side perspective view thereof;

FIG. 3 is a left side elevational view thereof, the right

side elevational view being identical thereto; and

FIG. 4 is a front elevational view thereof.

FIG. 1.

FIG. 3.

FIG. 2.

FIG. 4.
